ELECTRIC VAPORIZER

Joseph Robinson, New York, N. Y., assignor to
William R. Warner & Co. Inc., New York, N. Y.,
a corporation of Delaware

Original application March 27, 1939, Serial No.
264,358, now Patent No. 2,283,952, dated May
26, 1942. Divided and this application May 25,
1942, Serial No. 444,360

7 Claims. (Cl. 219—38)

This application is a division of my copending application Serial No. 264,358, filed March 27, 1939, now Patent No. 2,283,952, the subject matter of this application being disclosed in Figures 21 to 24 inclusive of that application.

My invention relates to electric vaporizers of the hand type for generating hot medicated vapors for inhalation in the relief of head colds, sinus infection, catarrh, and other afflictions of the upper respiratory organs. Among the objects is to simplify and improve vaporizers of this type, and to arrange so that the nasal piece or cover whilst readily applicable to and removable from the base or handle of the vaporizer will have a binding or wedging fit therewith that secures it against accidental dislodgement therefrom and resulting breakage. These and other objects of my invention will be explained in more detail in the following description, and are illustrated in the accompanying drawing in which

Figure 1 is a vertical section, approximately twice size, through my improvement;

Figure 2 is a plan view of the heater shown in Figure 1. In this view the container is omitted;

Figure 3 is a side elevation of the heater disclosed in Figure 2, showing a part of the insulating cover of the heater broken away, and

Figure 4 is a vertical section through the container and heater assembly shown in Figure 1 illustrating a modification of the method of "packing" the heater within the sealed container-heater unit comprising the parts 38, 73 and 122.

Referring to the drawing: My improved vaporizer includes a container E comprising a single piece of metal turned back on itself to form the cup 38 and the skirt 39. At its lower end the skirt is outwardly flared or tapered as shown at 121 and is pressed tightly over a hollow metallic base 122, the fit between these two parts being liquid tight. The skirt 39 is then spun or turned over the bottom of the base 122 as at 123. Within the base 122 a suitable heater D is mounted before the parts are assembled so that when the sleeve is turned over at 123 the heater is positively locked and sealed in the sleeve and against the cup 38. The heater includes a ceramic base 127 and a suitable resistance coil 73 mounted thereon. The cables of the electric cord 32 are connected to the resistance coil in any suitable manner as by metallic strips 124. The metallic base 122 is reduced in diameter to form a neck 125 which is pressed into or otherwise secured to the handle A as shown in Figure 1, the connection between the handle and the neck being liquid tight. When thus assembled none of the contents

of the cup 38 that might spill over can reach the heater D.

A cap or cover B, having a tapering nozzle 78, is set over the container E and for a short distance at its bottom has a wedging fit with the bulge 121 of the sleeve 39 to prevent wobbling of the cover B on the container E and accidental dislodgement therefrom. The cover is provided with a plurality of vertically extending serrations or grooves 79 through which, on inhalation, small streams of air flow into the cup 38 where they entrain the vapors and are directed to the nasal passages by the nozzle 78, the air currents being heated in this journey by the hot walls of the

10 container E. The modification shown in Figure 4 consists merely in substituting a pliable insulating packing 126 for the ceramic base 127 shown in Figure 1. In either of these embodiments of my invention it will be understood that the resistance coil 73, when covered with a suitable insulation, such as the asbestos covering shown in these figures, may be tightly packed or wadded in the metallic housing 122 without the use of a ceramic base or other extra insulating material.

15 My improvement does not employ a switch other than the one at the electric socket into which the vaporizer is plugged. If no switch is present in such socket, the conventional plug (not shown) in the outer end of the cord 32 is pulled out of the electric socket, thus breaking the circuit. To free the terminal connections 124 of any undue strain during this operation, or from other cause, a suitable stop or clamp 128, through which the electric cord 32 passes, is tightly pressed into the 20 handle A, or is otherwise secured thereto, and the cord is knotted above the stop at 129 for relief engagement with the latter.

The right is reserved to file a divisional application or applications covering any of the subject matter of this application which may not be claimable herein and no abandonment is made of any subject matter not adequately claimed herein.

What I claim is:

- 45 1. An electric vaporizer comprising in combination, a handle, a heater and container sealed in liquid tight relation with respect to each other and supported on the upper portion of said handle, a cover mounted on said container for 50 directing the vapors and for insulating the container, said cover and container having wedging engagement one with the other whereby accidental dislodgment of the cover from the container is prevented, the wedging engagement between the cover and the container being secured

by providing the container with a skirt and flaring the skirt outward to wedgingly engage interior surfaces of the cover.

2. A vaporizer according to claim 1 in which the container comprises a pair of hollow parts (E and 122, Figure 1) joined together with the heater permanently sealed liquid tight in the housing formed by said joined parts.

3. A heater-container unit for electric vaporizers, said unit comprising a container for the substance to be vaporized, a part connected to the bottom of said container in liquid tight relation thereto to form a housing, and a heater in said housing and permanently sealed liquid tight therein, in combination with a cover for covering said heater-container unit and for insulating the same, said cover serving also to direct the vapors, and flaring means for providing wedging engagement between an inner portion of said cover and an outer surface of said housing whereby accidental dislodgement of the cover from the housing is prevented.

4. A heater-container unit for electric vaporizers, said unit consisting of a pair of tubular members of different diameters joined together in liquid tight relation to form a housing and extending away from each other on a common axis, one of said members being provided with a

container for the substance to be vaporized, and a heater arranged within said housing and permanently sealed liquid tight therein, in combination with a cover fitted over the member that is provided with said container so as to be substantially co-extensive with the area of the sides of the heater, said cover serving to insulate said heater-container unit and to direct the vapors, and a handle secured to the other of said tubular members.

5. A vaporizer according to claim 4, in which the tubular members are joined, and the heater is sealed liquid tight in said housing, by turning the lower edge of one of said members over a shoulder on the other member.

6. A vaporizer according to claim 4, distinguished further by providing said cover with a plurality of serrations through which, on inhalation, currents of air flow along and in contact with the outer surface of the heater-container unit and are heated thereby.

7. A vaporizer according to claim 4, distinguished further by securing an electric cord to said heater by means of suitable terminals and by providing said handle with means which contacts with said cord to free said terminals of the strains of service.

JOSEPH ROBINSON
